UNITED STATES PATENT OFFICE.

WILLIAM E. ZINGSHEIM AND JOHN L. STUBBS, OF PORTLAND, OREGON.

SLEEPING-PORCH.

1,279,819.

Specification of Letters Patent. Patented Sept. 24, 1918.

Application filed January 17, 1917. Serial No. 142,883.

To all whom it may concern:

Be it known that we, WILLIAM E. ZINGSHEIM and JOHN L. STUBBS, citizens of the United States, residing at Portland, in the 5 county of Multnomah, State of Oregon, have invented a new and useful Sleeping-Porch, of which the following is a specification.

This invention relates to sleeping porches, one of its objects being to provide a structure 10 adapted to be movably connected to a building so that, when not in use, it will be concealed within the structure but, when it is desired to use the same, it can be projected beyond the wall of the structure by mechanism 15 under the control of a person within the structure.

A further object is to provide a structure of this type which has a sectional floor adapted to collapse automatically when the 20 mechanism is retracted out of active position and which will automatically move into operative position when the sleeping porch is moved outwardly from the building.

A still further object is to provide means 25 whereby when the mechanism is housed, the front rail thereof will constitute the sill of windows.

With the foregoing and other objects in view which will appear as the description 30 proceeds, the invention resides in the combination and arrangement of parts and in the details of construction hereinafter described and claimed, it being understood that changes in the precise embodiment of the invention herein disclosed, can be made within 35 the scope of what is claimed, without departing from the spirit of the invention.

In the accompanying drawings the preferred form of the invention has been shown.

40 In said drawings:—

Figure 1 is a central vertical section through a sleeping porch embodying the present improvements, the same being shown projected to active position.

45 Fig. 2 is a plan view of said structure, parts being broken away and the adjoining portion of the wall of the building being shown in section.

Fig. 3 is a vertical transverse section on 50 the line 3—3 Fig. 1.

Fig. 4 is a longitudinal section through the sleeping porch, the same being shown partly extended.

55 Fig. 5 is a detail view of one of the side panel operating wheels and some adjacent parts.

Referring to the figures by characters of reference 1 designates a portion of the wall of a building, the same being provided with an opening 2 normally closed by hinged doors 3. Each of these doors is preferably formed of an upper section 4 having the appearance of a window and a lower section 5 which can be made solid so as to have the appearance of a portion of a door. Any 60 suitable means may be provided whereby the upper and lower sections can be connected together so as to swing as one body after the manner of a door or, if desired, the upper section can be unfastened from the lower 65 section so as to swing outwardly in the same manner as a hinged window.

The sections 5 are set back from the outer face of the wall 1 and the space in front of these sections is normally filled by a railing 75 section made up of a transverse base beam 6, a sill 7 and a connecting panel 8. When these parts are seated within this space the sill 7 is arranged close under and projects outwardly from the upper sections 4 and the beam 6 rests against the lower portions of the lower sections 5, there being a space thus left between the panel 8 and the sections 5.

Hingedly connected to the sides of the opening 1 are side panels 9 adapted to 80 swing inwardly against the panels 5 and to rest in lapped relation so as thus to partly fill the space between the panels 5 and the panel 8. The balance of the space between the folded side panels 9 and the panel 8 is 85 filled by a floor section 10 which is hinged along one edge to a projecting ledge 11 constituting a continuation of the floor 12 of the building structure. Another floor section 13 also occupies this space under normal 90 conditions and one end of the section 13 is connected to the bottom of the floor 12 by one or more flexible straps 14 or the like. The two sections 10 and 13 are adapted to extend parallel with each other between the 95 panels 5 and 8. Section 13 is connected at its upper or outer edge to chains 15 which pass upwardly over sprockets 16 arranged under the sill 7. From these sprockets the chains extend downwardly close to and back 100 of the panel 8 to sprockets 17 under beam 6 and thence inwardly to sprockets 18 arranged under the opening 2 and secured to a transverse shaft 19 journaled in the wall of the structure 1. Weights 20 are connected 105 to the inner ends of these chains and serve to hold said chains normally taut.

Fig. 4 is a longitudinal section through the sleeping porch, the same being shown partly extended.

Fig. 5 is a detail view of one of the side panel operating wheels and some adjacent parts.

The beam 6 is secured upon the outer ends of supporting beams or girders 21 having longitudinal racks 22, said girders and racks being extended through openings under the 5 floor 12 and within the wall 1 and being supported on gears 23 secured to the shaft 19 and which are of less diameter than sprockets 18. Guide rollers 24 are arranged between the joists 25 on which the floor 12 is 10 mounted and the beams or girders 21 are adapted to work between these rollers. Top strips 26 are secured on the beams or girders 21 and have their upper faces flush with the top face of the beam or cross member 6, 15 these strips 26 being adapted to extend up to the ledge 11 when the porch is extended to active position.

A gear 27 is secured to the shaft 19 and meshes with a gear 28 secured to an intermediate shaft 29. This shaft in turn has a gear 30 meshing with a gear 31 which is secured to a shaft 32 extending into the building structure from the wall 1 and provided with a crank 33 or other suitable 25 means whereby it can be rotated by an occupant of the building structure.

Assuming that the floor sections 10 and 13 are standing on edge in the space between the panels 5 and the panel 8 and 30 that the sill 7 is drawn up against the lower edges of the window sections 4, the sleeping porch can be extended outwardly to active position by rotating shaft 32 and causing motion thus to be transmitted to the shaft 35 19. Consequently gears 23 will push the racks 22 and the parts carried thereby outwardly from the wall 1 and at the same time the sprockets 18 will pay out the chains 15. One or more straps 34 are attached to the 40 outer or upper edge of the section 13 and extend downwardly under guide sheaves 35 carried by the cross member 6 and thence inwardly where they are mounted on pulleys 36. Thus when the structure is moved outwardly as described, and the chains 15 are 45 paid out, the straps 34 will pull downwardly on the outer edge portion of the floor section 13 while said floor section will be slid outwardly with the panel 8 as it is gradually lowered. The floor section 10, which rests 50 on the section 13 will swing downwardly by gravity and, when the porch has been fully extended, the two sections 10 and 13 will thus be brought into horizontal positions 55 with their inner edges close together. The inner or meeting edges of the two sections 10 and 13 are preferably beveled as shown, so as to lap. After the structure has thus been extended, the side panels 9 can be 60 swung outwardly by any suitable means provided for that purpose and which means are preferably actuated from within the building structure. These side panels will be brought to a stop against side cleats 36' 65 extending inwardly from the sides of the

panel 8 and when the side panels have thus been positioned, the two sections 4 and 5 can be opened outwardly after the manner of a door so as to permit access to be had readily to the porch. When it is desired to 70 house the porch, the sections 4 and 5 are closed, the side panels 9 are swung to lapped position under the sections 4 and the rotation of shaft 19 is reversed so as to cause the racks 22 to move inwardly under the 75 floor 12. Thus the sprockets 18, which are of greater diameter than the gears 23, will pull on the chains 15, moving them faster than the racks 22, and cause the outer edge of the panel 13 to be moved upwardly and 80 the beveled edge of the section 13 will act as a wedge whereby said section 13 will work under the beveled edge of the section 10 and gradually elevate said section 10 as the structure is being moved inwardly until 85 the parts ultimately assume their housed positions.

The straps 34 which are mounted on the pulleys 36 are provided with weights 37. This arrangement will prevent the intermediate portions of the straps from becoming slack and hanging downwardly during the housing of the structure.

An awning 38 may be erected on the wall 1 and can be so proportioned as to cover 95 the sleeping porch when extended. The awning can be of any preferred construction and constitutes no part of the present invention.

As has heretofore been stated, various 100 means may be employed for actuating the side panels so as to move them into or out of active position. For example, a shaft 39 may be extended transversely under the door structure and the floor adjacent thereto and mounted on this shaft under the side portions of the door may be broad spaced wheels 40. Each wheel has a guide channel 41 therein provided with portions close to and parallel with the respective sides of 105 the wheel and with an intermediate obliquely disposed portion 42. The side panels 9 have pivot rods 43 extending downwardly from their inner ends and secured to the lower ends of these rods are arms 44 having studs 110 45 which work within the grooves 41 and 42. Shaft 39 is provided at one end with a gear 46 meshing with a gear 47 secured to the lower end of a vertical shaft 48. To the upper end of this vertical shaft is secured a gear 49 which is adapted to receive motion through a gear 50 from a crank arm 51 arranged inside of the building. Thus after the floor of the porch has been extended as hereinbefore described, the crank 120 51 can be rotated for the purpose of rotating the shaft 39, whereupon the wheels 40 will revolve and cause arms 44 to swing through 90 degrees with the result that the panels 9 will be swung from their innermost or 125 130

lapped position outwardly to their extended position, thus to close the sides of the sleeping porch. Prior to retracting the sleeping porch, the side panels can be folded inwardly against the lower sections of the door by reversing the foregoing operation.

What is claimed is:—

1. The combination with the wall of a fixed structure having an opening therein, and a floor extending into the opening, of a slideable structure mounted to work below the floor and to project therebeyond, an end railing carried by said structure and adapted to occupy the lower portion of the wall opening when the structure is housed below the floor, floor sections collapsible to position back of the railing and adapted to be concealed thereby, means for shifting the slideable structure outwardly from the wall of the fixed structure, and means for automatically laying the floor on said slideable structure during such movement.

2. The combination with the wall of a structure having an opening therein, and a floor extending into the opening, of a slideable structure mounted to work below the floor and to project therebeyond, an end railing carried by said structure and adapted to occupy the lower portion of the wall opening when the structure is housed below the floor, floor sections collapsible to position back of the railing and adapted to be concealed thereby, means for moving said slideable structure into housed position, and means controlled by such movement for collapsing the floor into position back of the railing.

3. The combination with the wall of a structure having an opening therein, and a floor extending into the opening, of a slideable structure mounted to work below the floor and to project therebeyond, an end railing carried by said structure and adapted to occupy the lower portion of the wall opening when the structure is housed below the floor, floor sections collapsible to position back of the railing and adapted to be concealed thereby, means for shifting the structure outwardly from the wall of the structure, means for automatically laying the floor on said structure during such movement, side panels adapted to be housed back of the railing, and shiftable laterally to positions above the sides of the floor on the slideable structure.

4. The combination with the wall of a structure having an opening, and sectional closures for said opening, each closure having an upper and a lower section, of a slideable structure adapted to be housed within the first named structure, a railing carried thereby and normally housed within the lower portion of the wall opening and providing a sill for the upper sections of the closure, a sectional floor normally collapsed

back of the railing, means for shifting the slideable structure outwardly from the wall, and means for automatically laying the collapsible floor during such outward movement.

70

5. The combination with the wall of a structure having an opening, and sectional closures for said opening, each closure having an upper and a lower section, of a slideable structure adapted to be housed within the first named structure, a railing carried thereby and normally housed within the lower portion of the wall opening and providing a sill for the upper sections of the closure, a sectional floor normally collapsed back of the railing, means for shifting the slideable structure outwardly from the wall, means for automatically laying the collapsible floor during such outward movement, and side panels shiftable to position between the railing and the sides of the wall opening, said panels being normally housed back of the railing and transversely of the opening.

75

6. The combination with a building structure having an apertured wall and a floor

at the bottom of the aperture and providing a ledge, of a slideable structure normally housed under the floor and including a rack, an end railing carried by said structure and normally housed within the lower portion of the opening, said end railing forming a sill, sectional closures within the opening, said closures consisting of upper and lower sections, the upper sections normally extending downwardly to the sill, a floor section hingedly connected to the ledge and normally upstanding between the closure and the railing, another floor section normally interposed between the hinged floor section and the railing, a flexible connection between said last named floor section and the ledge, means connecting said floor section to the sill, and means for simultaneously shifting the slideable structure and said connection to move the railing outwardly from the opening and to lower the floor sections.

95

7. The combination with a building structure having an apertured wall and a floor at the bottom of the aperture and providing a ledge, of a slideable structure normally housed under the floor and including a rack, an end railing carried by said structure and normally housed within the lower portion of the opening, said end railing forming a sill, sectional closures within the opening, said closures consisting of upper and lower sections, the upper sections normally extending downwardly to the sill, a floor section hingedly connected to the ledge and normally upstanding between the closure and the railing, another floor section normally interposed between the hinged floor section and the railing, a flexible connection between said last named floor section and the ledge,

100

105

110

115

120

125

30

means connecting said floor section to the sill, means for simultaneously shifting the slideable structure and said connection to move the railing outwardly from the opening and to lower the floor sections, and weighted means for facilitating the lowering of the sections.

8. The combination with a building structure having an apertured wall and a floor 10 at the bottom of the aperture and providing a ledge, of a slideable structure normally housed under the floor and including a rack, an end railing carried by said structure and normally housed within the lower portion 15 of the opening, said end railing forming a sill, sectional closures within the opening, said closures consisting of upper and lower sections, the upper sections normally extending downwardly to the sill, a floor section hingedly connected to the ledge and normally upstanding between the closure and 20 the railing, another floor section normally

interposed between the hinged floor section and the railing, a flexible connection between said last named floor section and the ledge, 25 means connecting said floor section to the sill, means for simultaneously shifting the slideable structure and said connection to move the railing outwardly from the opening and to lower the floor sections, and side 30 panels normally extended transversely of the opening and back of the railing and shiftable angularly to close the spaces between the railing and the wall when said railing is projected beyond the wall. 35

In testimony that we claim the foregoing as our own, we have hereto affixed our signatures in the presence of two witnesses.

WILLIAM E. ZINGSHEIM.
JOHN L. STUBBS.
